AUTOMOBILE DISK WHEEL

Paul D. Fadow, % The Budd Co., 12141 Charlevoix Ave.,
Warren, Mich.

Filed June 27, 1962, Ser. No. 70,704

Term of patent 14 years

(Cl. D14—30)

FIG. 1 is a perspective view of an automobile disk wheel embodying the new design;

FIG. 2 is a full offset section taken at the studs and between the studs of the wheel of FIG. 1;

FIG. 3 is an enlarged partial elevation of the recessed stud area of the disk wheel;

FIG. 4 is a section taken at lines 4—4 of FIG. 3.

The essential features of the design reside in the disk wheel shown in full lines in the drawings.

I claim:

The ornamental design for an automobile disk wheel, substantially as shown and described.
